ANTENNA INTERACTION COMPENSATING
MEANSArmig G. Kandoian, New York, N. Y., assignor
to Federal Telephone & Radio Corporation, a
corporation of Delaware

Application October 23, 1941, Serial No. 416,163

4 Claims. (Cl. 250—11)

This invention relates to method and means for compensating interaction between antenna elements and more particularly to an arrangement for compensating interaction between antenna elements of a radio beacon.

A radio beacon with quadrant identification has been proposed in which two separate radio beacon arrays are arranged at right angles to one another, the beacons each consisting of several units. In this proposed system two of the antenna units are arranged directly in vertical alignment. A means was proposed in this system for compensating somewhat the interaction between these vertically arranged units. It has been found, however, that with this arrangement interference occurred at high altitudes within the angle of about 90° subtended directly above the beacon, due to uncompensated minor lobes.

It is a principal object of my invention to provide a method and means for compensating precisely the reaction between two closely related antenna elements so as to avoid interference due to minor lobes at any angle.

According to a feature of my invention compensation for interaction is attained by feeding energy from one of the antennae of the system to the interfering antenna unit and to position the feed line interconnecting the antennae and control the phase of energy conducted over the feed line to substantially completely neutralize all parasitic effects.

A better understanding of my invention and the objects and features thereof will be had from the particular description of a preferred embodiment thereof made with reference to the accompanying drawing, in which

Fig. 1 is a schematic diagram of a preferred embodiment of the radio beacon incorporating the features of my invention;

Fig. 2 is a diagrammatic illustration of radiation diagram produced by such a radio beacon.

In Fig. 1 is shown a radio range beacon comprising antennae 2, 3 and 4 to which energy is supplied from transmitter 1 over modulators 10 and 11, and network 12. Central antenna unit 3 is supplied over the line 17 connected to network 12. The energy thus supplied to these antenna units will produce a field pattern such as shown at 286, Fig. 2. At right angles to the beacon comprising antennae 2, 3 and 4 is provided a further beacon arrangement consisting of antennae 2A, 3A and 4A. Energy from source 1 and from a tone source 15 is fed to modulator 14 which is preferably a balanced modulator and from 14 energy is supplied to a keying reversing

switch 16 to the two side radiators 2A and 4A. Another portion of the energy from modulator 14 is fed over line 17A to antenna unit 3A. This energy supplied to the auxiliary or identification beacon contains only side bands which may be received on an aircraft with the carrier frequency transmitted from antenna 3.

Antenna units 2 and 4 are connected in a manner to prevent parasitic effects due to energy from antennae 3 and 3A. Similarly antenna units 2A and 4A are arranged to prevent parasitic effects due to energy from antennae 3A and 3. This arrangement then prevents any parasitic action of the side radiators 2, 4, 2A or 4A, because of any radiation effects at 3 or 3A. There remains, however, a certain amount of interaction between units 3 and 3A.

In a proposed arrangement this parasitic action was partially compensated by feeding energy between lines 17 and 17A. The adjustment for this purpose was achieved by moving one connection point of a line interconnecting lines 17 and 17A along conductors 17 or 17A until no interaction effect was noticed between lines 17 and 17A. It was found, however, that at high altitudes there were troublesome multiple lobes or cross-over effects due to interaction between antennae 3 and 3A.

The proper points of connection for a feed line to compensate or neutralize completely parasitic effects both between 17 and 17A as well as between 3 and 3A should be made at a point electrically equal to a half-wave length of the operating frequency from each of the antenna units. These points may be most readily checked by the following method. Antenna 3 may be energized while line 17A is completely disconnected from any energizing source. A short circuiting bar is then moved along line 17A until a point is reached at which the induced current in antenna 3A reduces to zero. A similar test is then made of line 17 by energizing antenna 3A and disconnecting line 17 from any source of supply. If, then, an interconnection is made between lines 17 and 17A at the points where the induced currents reduce to zero and the phase and amplitude of the energy fed between these lines is properly adjusted, a complete compensation will take place and no interaction between the units will then occur.

In order to provide a readily adjustable interconnection, preferably, short circuited quarter wavelength transmission line sections 18, 18A are bridged across lines 17, 17A, respectively. At chosen points on sections 18, 18A is connected line 19, preferably provided with one or more

phase shifting units 20, 20A. The point of connection may be adjusted to control the amount of energy tapped. These phase shifting units are preferably made of "trombone" transmission line sections so that the phase shift is accomplished by altering the length of line 19. At an intermediate point of line 19 is arranged a resistance element 21 for dissipating a percentage of the energy. By providing this resistance unit suitable phase shifting can be provided for so that the interconnecting line may properly be connected at the effective half wavelength points as outlined above.

Sections 18 and 18A may be completely eliminated if desired but in general it is preferable to have at least one such section as otherwise it would be necessary to dissipate a large percentage of the energy normally fed to the antenna unit in order to provide for sufficient compensating phase shift. Likewise, only one phase shifting unit need be supplied although it is preferred to utilize two units so as to maintain the symmetry of the system.

The resistance unit 21 may be of any desired value although in some cases it is convenient to use a resistance equal to the surge impedance of the line. In an actual installation of the system made, the resistance 21 was of a value equal to the surge impedance of the line. In this same installation only one building out section was used but two phase shifters were provided. Actual tests made of a beacon constructed as outlined above showed no indication of any crossover or disturbance effect above the beacon at any point. The percentage of energy dissipated in the resistance unit was less than fifteen percent of that supplied to the feed lines.

I have described above the application of my invention to vertically arranged units of a radio beacon. It should be appreciated, however, that this compensating effect may be applied to any type of antenna arrays regardless of their use as radio beacons or the like. For example, it is clear that if multiple vertical lobes are bothersome in any vertical array, the principles of my invention may be readily applied to avoid this effect. Similarly, the compensating effect may be produced between horizontally arranged antenna units. It should likewise be clear that the type of units used is immaterial in so far as the principles of my invention are concerned. When long wavelengths are utilized other types of phase shifters than those described above may be used.

The specific example and illustration set forth above are used merely by way of example in explaining my invention. Many changes in the particular construction may be made without departing from the scope of my invention.

What I claim is:

1. Means for compensating or neutralizing interaction between antenna units which are arranged in close proximity to one another, and supplied with differently characterized energy over separate supply lines, said means including a compensating line interconnecting points on one of said supply lines with points on another of said supply lines, said points on any one of said supply lines being electrically spaced a distance

substantially equivalent to one half a wavelength at the operating frequency from said antenna unit on said respective supply line, a resistance unit bridged across said compensating line, and

5 means for adjustably controlling the amplitude and phase of energy in said compensating line.

2. Means for compensating interaction between antenna units according to claim 1, wherein 10 said means for adjustably controlling the amplitude includes a short circuited quarter wavelength transmission line section connected across one of said supply lines at said points therein, at least a portion of said line section being included 15 in said compensating line, adjustable connection points being provided on said section for varying the connection of said portion with said compensating line.

3. A radio beacon comprising a first array of 20 antenna units for producing a beacon effect, a second array of antenna units angularly related to said first array, at least one antenna unit of each array being arranged in close proximity to a unit of the other array, means for supplying differently characterized energy over separate supply lines to each of said arrays, and means, including a compensating line for compensating interaction between said closely spaced units, said compensating line interconnecting points on said supply line for one said antenna unit with points 25 on said supply line for said other antenna unit, said points on any one of said supply lines being electrically spaced a distance substantially equivalent to one half a wavelength at the operating frequency from said antenna unit on said respective supply line, a resistance unit bridged across said compensating line, and means for 30 adjustably controlling the amplitude and phase of energy in said compensating line.

4. The method of compensating interaction between two antenna units which are arranged in close proximity to one another, and supplied with differently characterized energy over separate supply lines, said method including energizing a 40 first of said supply lines while the second of said supply lines is disconnected from the energizing source, making a short circuit connection across said second supply line and varying the position of said connection along the line until a point is reached at which the current induced in the antenna unit connected with said second supply line reduces to zero, making a similar test by energizing said second supply line while said first supply line is disconnected from the energizing source, making a short circuit connection across said first supply line and varying the position of said latter connection along the line until a point is reached at which the current induced in the antenna connected with said first supply line reduces to zero, interconnecting the points in said two lines where the short circuit connections reduced the current to zero, for supplying energy compensating for the interaction between said antenna units, dissipating some of said compensating energy, and adjustably controlling the amplitude and phase of the remainder of said compensating energy.
